Primary Examiner — Andrew Kerr*Assistant Examiner* — Chariton Vas Alexakis(74) *Attorney, Agent, or Firm* — Calderon Safran & Cole PC(57) **CLAIM**

The ornamental design for a whisk, as shown and described.

DESCRIPTION

FIG. 1 is a perspective view of a whisk, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings depict portions of the whisk that form no part of the claimed design.
